(57) **CLAIM**

The ornamental design for a telephone holder, as shown and described.

DESCRIPTION

FIG. 1 is a front elevation view of the telephone holder, showing my new design;

FIG. 2 is a rear elevation view thereof;

FIG. 3 is a top elevation view thereof;

FIG. 4 is a bottom elevation view thereof;

FIG. 5 is a right side elevation view thereof;

FIG. 6 is a left side elevation view thereof;

FIG. 7 is a left side perspective view thereof;

FIG. 8 is a front perspective view thereof;

FIG. 9 is a front perspective view thereof, showing an unclaimed telephone being inserted into the telephone holder;

FIG. 10 is a front perspective view thereof, showing an unclaimed telephone partially inserted into the telephone holder;

FIG. 11 is a front perspective view thereof, showing an unclaimed telephone fully inserted into the telephone holder;

FIG. 12 is a front perspective view thereof, with the telephone holder expanded;

FIG. 13 is a front perspective view thereof, with the telephone holder partially expanded;

FIG. 14 is a rear elevation view thereof, showing the telephone holder expanded;

FIG. 15 is a top elevation view thereof, showing the telephone holder partially expanded;

FIG. 16 is a bottom elevation view thereof, showing the telephone holder partially expanded;

FIG. 17 is a right side elevation view thereof, showing the telephone holder partially expanded; and,

FIG. 18 is a left side elevation view thereof, showing the telephone holder partially expanded.

Broken lines shown on the edges of the telephone holder, adjacent to shaded areas, illustrate portions of the telephone holder that form no part of the claimed design. Additional broken lines showing a telephone in FIGS. 9, 10, and 11, depict environmental subject matter and form no part of the claimed design.

1 Claim, 18 Drawing Sheets
